MOTION-PICTURE COMBINATION

Carl Waldeyer, San Francisco, Calif.

Application September 11, 1944, Serial No. 553,629

18 Claims. (Cl. 88—16.6)

1

My invention relates to motion picture devices.

An object of this invention is to provide moving picture film, by novel production methods, adapted for projection in my invention, Patent No. 2,226,833, issued Dec. 23, 1941, and to which patent reference is hereby made.

A further object is to combine portions of the mechanism and actuating means of the patent with the novel features of my invention to produce the results described, illustrated and claimed in this application.

Another object of my invention is to produce photographic film suitable to be immediately projected, after processing, in the device herein described, and also to be adapted for projection in the patent device.

Another object of my invention is to make photographing and projection of motion pictures more economical by reducing the amount of film footage required by the methods now in use.

An object of this invention is to provide a motion picture device capable of producing film suitable for projection in the duplex type of projector, such as shown in the patent, without being subjected to the liability of parallax in projection.

A further object of this invention is to make the photographing and projection of motion pictures more economical by providing a single device adapted to both take and project the pictures.

Other objects of my invention will be apparent or will be specifically pointed out in the description forming part of this specification, but I do not limit myself to the embodiment of the invention described herein, as various forms may be adopted within the scope of the claims following the description.

My invention may be more fully understood by direct reference to the drawings.

In the five sheets of drawings:

Fig. 1 is a top or plan view of the actuating mechanism of this invention, shown mounted on the cover of the device. The cover is partly broken away to show the shutter actuating means suspended on underside of cover.

Fig. 2 is a section on line 2—2, Fig. 1, in direction of arrows, and shows an enlarged detail in front elevation of the shutter actuating mechanism.

Fig. 3 is a section on line 3—3 of Fig. 1, in direction of arrows and shows a side view detail, above the cover, of the mutilated gear drive for the film feed mechanism, and also shows the film feed sprocket barrels and gear suspended below the cover.

2

Fig. 4 shows an elevation from the front, looking rear, illustrating general arrangement of parts of a motion picture combination constructed in accordance with this invention.

5 Fig. 5 is a sectional plan view through 5—5 of Fig. 4 showing features of the invention when employed as a motion picture camera.

Fig. 6 is a front elevational view showing front wall with camera lens and attachments.

10 Fig. 7 is a front elevational view showing front wall with projection lens attached.

Fig. 8 is a side elevational view of a side wall illustrating the method of adapting projection shutters to be used on the device, on the outside 15 of side walls.

Fig. 9 is a side elevational view of a side wall illustrating the manner of adapting camera shutters to operate on the inside of the side walls of the device.

20 Fig. 10 is an elevational view showing oscillating disk and surfaced mirror and the manner of adapting same to oscillate on block and vertical pivot.

Fig. 11 is a side view illustrating driven gear 25 and film sprocket barrel, below the cover, and driving pinion above cover, being a part of the film actuating means.

Fig. 12 is a plan view looking up of Fig. 11, illustrating the film sprocket barrels and driven 30 gears, shown suspended under the cover.

Fig. 13 is an illustration showing a front view of a motion picture projector constructed in accordance with this invention.

35 Fig. 14 is an illustration showing a rear view of a motion picture camera constructed in accordance with this invention, and is a duplicate of Fig. 13 with lamp housings removed and a camera lens, not showing, substituted for the projection lens.

40 Fig. 15 is a side elevational view of a side wall, illustrating the manner in which the projection shutters may be adapted to act as closures when the device is being operated as a camera.

Fig. 16 is a side elevational view of one of the 45 film guides which are part of the inner side walls of the device.

In detail the construction illustrated in the drawings comprises the bed 1, disposed on any suitable support, as at 1', 1', 1', 1', Figs. 13 and 14. The vertical walls 2, 3 are integrally formed

50 on bed 1. They are set facing each other in parallel positions, and are spaced apart sufficiently to allow the installation of mechanism between them and at a distance to comply with focusing requirements, and are provided with

projection openings 4 and 5 disposed so as to be in axial alinement with each other. Fig. 5. See also Fig. 8.

These parallel walls 2 and 3 provide suitable mountings for the duplex lamp housings A and B. These lamp housings are alike in construction and function and are conventionally illustrated in the drawings. Fig. 13. They are removably attached to the respective parallel walls 2 and 3. Each housing is supplied with a lamp 7, and the customary condensing lenses 8. They are disposed on the said vertical walls so that the light beams from the respective lamps are in axial alinement with each other and with the respective projection openings 4 and 5. The light beams are also in alinement with an oscillating reflecting surface to be later described.

The parallel walls 2, 3 are each provided with vertical covered guideways 9 and 10 preferably set in recesses provided in the walls and having opposed vertical grooves therein to form vertical guide slots 12, 13 and 12a and 13a adapted to guide their respective films 14 and 15 through the focal plane. These respective channel guides 9, 10 are provided with covers 16, 16a to exclude light from the films except at exposure openings 17, 18 which are provided in each covered channel and disposed to be in axial alinement with each other and with the projection openings 4 and 5 in the respective parallel walls, and are also in the focal plane of the lens 28. These openings 17, 18 are adapted to admit light from the lens to the sensitised films at exposure periods. See Figs. 4, 5 and 16.

The shutters 19, 20 and 19a, 20a are similarly guided through the focal plane, laterally, in the horizontal guides 21, 22—23, 24 and 21a, 22a—23a and 24a. These shutters have the openings 25, 26 and 25a, 26a so that the respective shutters alternately expose light to the films. These shutters are driven in alternate relation so that one film is dark while the other is light. Fig. 5. See also Figs. 8, 9 and 15. These shutters are of the known kind, similar to those of the patent, but are arranged in a novel combination and actuated by an improved mechanism, as shown in the description and drawings.

The shutters 19 and 20, adapted to operate when the device is being used as a projector, are located outside of the respective parallel walls 2 and 3. By adapting the projection shutters to operate on the outside of the parallel walls heat from the lamps in the respective lamp houses A and B does not reach the films except during exposure periods. Figs. 5, 8 and 15.

When the device is being used as a camera the respective shutters 19a and 20a on the inner side of the respective parallel walls 2, 3, within the dark chamber 27, are adapted to operate. These inside shutters are necessary to protect the sensitised films, except at exposure periods, from being struck by light rays from the camera lens 28. See Figs. 5 and 9.

When the device is operating as a camera the outside shutters 19, 20 may be removed, and the respective projection orifices 4 and 5 may be supplied with closures or, preferably, the actuating means may be detached from the outside shutters and they may be disposed to act as closures. See Fig. 5 and also Fig. 15. When the device is being used as a projector the inside shutters 19a, 20a may remain in gear, as they are adapted to operate in synchronism with the respective outside shutters 19, 20, or they may be removed.

The vertical parallel walls 2, 3 are provided with a rear wall 29 integrally fixed therebetween, and made integral with the bed 1. Figs. 8 and 9. See also Figs. 14 and 15. The front ends of 5 parallel walls 2, 3 are respectively provided with a series of vertical opposed grooves 30, 30 and 31, 31, Fig. 5, adapted to have a movable front wall selectively disposed therein, at right angles to said parallel walls and resting on bed 1. Front 10 wall 32, with a projection lens 34 disposed therein, is adapted to be inserted in opposed grooves 30, 30 when the device is to be used as a projector. Figs. 5 and 13. Front wall 32a, with camera lens 28 disposed therein, is adapted to be inserted in opposed grooves 31, 31 when the 15 device is to be used as a camera. Fig. 5. See also Fig. 6.

Wall 32a, with camera lens 28 supplied with 20 automatic shutter 35 and shutter trigger 36, has movably disposed thereon a rod 37. Rod 37 is positioned on wall 32a so that its lower end is in operative contact with trigger 36 and its upper end extends to the top of the wall. A coiled spring 38 is disposed on rod 37 towards its top 25 and so adjusted that it gives a reciprocating movement to said rod, when pressed downward and released. Fig. 6.

The mechanism for providing an oscillating reflecting means for the device is best shown in 30 Figs. 4, 5 and 10. A block 39 is integrally set on bed 1 between parallel walls 2 and 3, within the dark chamber 27. Figs. 4 and 10. A vertical pivot 40 is integrally fixed in said block, said pivot adapted to be equidistant from parallel 35 walls 2, 3 and adapted to transversely cross the axial line of the light beams from the respective lamp housings A and B. Figs. 5 and 10. An oscillating disk, or turntable 41, provided with a center bore is set on block 39, revolvably engaging with pivot 40, said pivot forming the axis of the oscillating disk. A surfaced rectangular mirror 43 is integrally fixed on said disk 41, and disposed in perpendicular position. See Fig. 10. Said mirror 43 adapted to be revolvably engaged, 40 as at 6, Fig. 10, on said pivot 40.

The reflecting means may be improved, particularly for camera purposes, by substituting a prismatic mirror for the plane mirror, to operate as follows:

A vertical pivot 140 is integrally fixed on said 50 block 39, said pivot adapted to be equidistant from parallel walls 2, 3 and extending upward to a point slightly below the axial line of the respective exposure openings 17 and 18. An oscillating disk or turntable 141, provided with a center bore is set on block 39, said disk 141 being provided with a perpendicular post 142 integrally fixed thereon, said post provided with a vertical bore which registers with the center bore on said disk 141. Said disk and said post being adapted to revolvably engage on vertical pivot 140, said pivot forming the axis of said disk and said post. A right angle prismatic mirror 143 is adapted to be disposed on top of said post 142 and made integral therewith. See Figs. 4 and 5. The 60 actuating means for operating the said disk 141 and the said disk 141 are the same, and will be later described.

A removable cover 44 is provided for the device as shown in Figs. 1 and 3. This cover sets on top of the front and back walls 29 and 32 and the said parallel walls 2 and 3, and is removably fastened to same in any suitable manner. Figs. 8, 14 and 15. This cover 44 when in place provides 70 a dark chamber 27 for the device in the area en-

closed between the front and back walls 29 and 32, and the respective parallel walls 2 and 3. See Figs. 4 and 5.

The driving mechanism for actuating the films, the shutters and the oscillating mirror is best shown in Figs. 1 and 2. See also Figs. 5, 8 and 9. Parallel driving shafts 45 and 46 are disposed in lengthwise positions on the movable cover 44, and rotatably mounted in bearings 47-48 and 49-50 on top of the said cover. The left hand member 45 of the said duplicate shafts is provided with a manually operated crank 51, fixed to rear end of said shaft. Shaft 45 may also be operated by any suitable power means. Miter gears 52 and 53 of identical ratio are fixed on the contiguous front ends of said parallel driving shafts. A cross shaft 54 similarly revolves in bearings 55-56 on the said cover 44, and extends between the said parallel shafts 45-46, at the front ends thereof. Miter gears 57-58 of like ratio to said miter gears 52-53 are fixed on the respective ends of said cross shaft 54, and are engaged, respectively, with the respective miter gears 52-53 disposed on the ends of the said parallel shafts 45-46. Fig. 1.

The connection between the said parallel shafts 45 and 46 by the medium of the said cross shaft 54 and the miter gears 52-53 and 57-58 is so arranged that when the crank operated shaft 45 is revolved in a clockwise direction the companion shaft 46 revolves counterclockwise. Fig. 1.

The shutter actuating means operates as follows: The shutter arm 59 is fixed upon a cross shaft 60 which oscillates in its respective bearings 61-62 disposed on the underside of the removable cover 44, and at the rear thereof and transversely of the said parallel shafts 45-46. Fig. 1. The hub 63 of the shutter arm 59 is cut away to form shoulders 64-65 for alternate impingement of the cams 66-67 fixed on the crank driven shaft 45, to alternately swing the shutter arm 59. See Fig. 2. In the shutter actuating means shown in the invention, as described and illustrated herein, there is improvement and elimination of parts over the similar devices of the patent.

An alined shaft 68 is disposed in the dark chamber 27, slightly above bed 1. This alined shaft is parallel to cross shaft 60, but considerably below and somewhat forward of same. This alined shaft oscillates in bearings 69-70, respectively, fixed in the respective parallel walls 2-3, the ends of said shaft extending through said walls, projecting somewhat beyond their respective bearings. Fig. 5. See also Figs. 8 and 9. Upward extending arms 71 and 72 are fixed on the respective ends of said alined shaft 68, on the outside of the respective parallel walls 2 and 3. See Figs. 5 and 8. Similar arms 73 and 74, respectively, are fixed on the said alined shaft 68, on the inside of and contiguous to the said respective parallel walls 2 and 3, within said dark chamber 27. See Figs. 5 and 9. An upward extending arm 75 is fixed on said alined shaft 68 approximately at its center, between said parallel walls. This single center arm 75 is connected by link 76 with the said shutter arm 59. See Figs. 1 and 5. Arms 71 and 72, respectively, are connected by links 77 and 78 with shutters 19 and 20 disposed, respectively, on the outside of said parallel walls. Fig. 8. Arms 73 and 74, respectively, are connected by links 79 and 80 with shutters 19a and 20a disposed, respectively, on the inside of said parallel walls, within said dark chamber 27. Figs. 5 and 9. A pivot pin 81 is fixed

on the periphery of said oscillating disk 141. A link 82 connects this pivot pin 81 with the said upward extending arm 75 fixed on alined shaft 68. Fig. 5. Said arm 75 being also connected by link 76 with the shutter arm 59. See Fig. 1 and Fig. 5. The films move forward one space, alternately, for each half-turn of the driving rod, this movement allowing each film a protracted dwell while in exposure position within the dark chamber. The film shutters, and also the oscillating prism, must move more rapidly to provide a refinement of action in accord with the objects of the invention. As already shown these two devices are actuated by being attached to arms which are, in effect, in each case the long arm of a lever, and their respective movements are practically instantaneous. They are adapted to remain continually at rest, except for instantaneous movements, back and forth, to perform the functions outlined for them, which also allows them a protracted period of rest between movements.

Two countershafts 83 and 84, respectively, are revolvably disposed in bearings 85-85 and 86-86 fixed on top of said removable cover 44, in positions parallel to the said duplicate drive shafts 45 and 46. Mutilated pinions 87 and 88 are fixed on the respective countershafts 83 and 84, said pinions engaging cooperating mutilated drive gears 89 and 90, respectively, fixed on the said parallel drive shafts 45 and 46. See Fig. 1 and Fig. 3. These countershafts 83 and 84 are adapted, respectively, to be alternately driven by the said respective mutilated gears 89 and 90 upon the revolution of the said respective parallel drive shafts 45 and 46. Said countershafts 83 and 84, respectively, have also fixed thereon pinions 91 and 92 for purposes hereinafter explained. See Fig. 1 and Fig. 11. The main drive shaft of the patent and the countershafts attached thereto by mutilated gear connections is similar to the gear described herein, with the exception that the two sections of the drive shaft are disposed in parallel positions, and are connected by a cross shaft and miter gears instead of the universal joint of the patent. These respective countershafts and the cross shaft have additional novel gear disposed thereon to operate mechanism described in the invention.

Countershafts 93 and 94 revolvably set in bearings 95-95 and 96-96, respectively, are disposed on the underside of said removable cover 44, and substantially in vertical alinement with shafts 83 and 84 on top of said cover. These respective countershafts 93 and 94 have fixed thereon film feed barrels 97 and 98, each barrel provided with sprocket teeth. Said sprocket toothed barrels are provided, respectively, with rollers x1, x2, x3, and x4, x5, x6, said rollers being adapted to hold the respective films 14 and 15 in engagement with the sprocket teeth on the respective film feed barrels 97 and 98 in the known manner. Figs. 3 and 4. See also Figs. 11 and 12. The respective sprocket-barrel shafts 93 and 94 have fixed thereon driven gears 99 and 100, respectively. Said gears adapted to engage, through openings provided in cover 44, the driving pinions 91 and 92 fixed, respectively, on countershafts 83 and 84, mounted on top of said removable cover. Figs. 1 and 3. See also Figs. 11 and 12. This arrangement adapts said countershafts 93 and 94, respectively, to have mutilated gear connection with the said driving shafts 45 and 46, whereby an alternate.

and intermittent motion is transmitted to the said respective sprocket-barrel shafts.

On cross shaft 54 there is fixed, between the respective miter gears 57 and 58, a cam 101 having opposed lugs 101a and 101b thereon. Said cam 101 is adapted to be in operative contact with the rod 37 positioned on the front wall 32a. See Figs. 1 and 6.

The film feeding and timing mechanism of films 14 and 15 are alike, and only the progress of one film will be described in detail, and the same reference numerals applied to the other with the addition of the letter *a*. The action of the device will be described when used as a camera, with lamp housings removed and projection openings 4 and 5 closed by adapting projection shutters 19 and 20 to be used as closures, as shown in Figs. 5 and 15. To transfer the device from a camera to a projector it is only necessary to attach the lamp housings A and B and substitute the projection lens 34, Fig. 7, for the camera lens 28, Figs. 5 and 6.

Referring to Fig. 4 the conventional type of film reel 102 is disposed on stud pin 103 journaled in wall 104 of reel housing 105 suspended below bed 1. A locking device 106 is pivoted on roof of the housing 105 to hold film-feed reel 102 in place and to apply sufficient tension thereto to hold film 14 taut. A removable cover 108 is adapted to be fitted to open side of housing 105 to make same light proof. Duplicates of removable cover 108 are provided for the four reel housings. The film 14 wound on reel 102 enters dark chamber 27 through a projection of covered film guide 9, Figs. 4 and 16, extending below bed 1 and into reel housing 105 through a slot 105a provided in roof of reel housing. The sensitised film passes upwardly through the covered film guide 9 and through the focal plane at exposure opening 17. See Figs. 5 and 16. The film passes out of the film guide and, still in the dark chamber, engages with the sprocket teeth on barrel 97 disposed on underside of cover 44. Figs. 3 and 4. A covered way 109 is provided between end of film guide 9 and the sprocket barrel 97 to guard the sensitised film 14 from any light flashes proceeding from the camera lens 28. Fig. 4. The film 14 after engaging the sprocket teeth on barrel 97 passes out of dark chamber by slot 110 provided in removable cover 44. Figs. 1 and 4. The film is held in place on teeth of sprocket barrel 97 by rollers 21, 22 and 23. Fig. 3. The film then passes through a covered way 112 and enters upper reel housing 113 through floor 114 by slot 114a in said floor. Figs. 4 and 14. The open side of reel housing 113 is adapted to be closed, and made light proof, by duplicate removable cover 108. The reel housing 113 is positioned above cover 44 and removably fastened on floor 114, the reel housing is supported by legs *f*, *f* and *g*, *g*, resting on bed 1 and made integral therewith. See Figs. 13 and 14. The exposed film is progressively taken up on reel 115 mounted on stud pin 116 journaled on wall 117 of reel housing 113. The stud pin 116 is driven by the pulley 118 on the drive shaft 45 and the elastic belt 119 passing over the pulley 120 fixed on an extension 121 of stud pin 116 on outside of wall 117 of reel housing 113. The elastic belt 119 is crossed to revolve reel 115 in proper direction. A duplicate of pulley 118 may be fixed on an extension of sprocket barrel shaft 93, not illustrated, and elastic belt 119 may be attached to the pulley on shaft 93 in preference to the pulley on main driving shaft. See Fig. 4. Also 75

Figs. 13 and 14. Film 14 is held under steady tension between film feed sprocket barrel 97 and the upper take-up reel 115 by the pull of said reel and the said film is held under similar tension 5 between the film feed barrel and lower feed reel 112 by the pull of the sprocket teeth on said barrel and the resistance of said lower reel. The tension of film 14 above and below film feed barrel 97 is thus equalized and there is no appreciable 10 wear on the film by the pull of the said sprocket teeth. This action is made possible through the elimination of loops on the said film. The film moves in a straight rigid line from the lower to the upper reel except for the necessary diversion 15 to wind partly around the film feed sprocket barrel 97. This arrangement also allows elimination of pulley and belt generally relied on to actuate the film feed reel.

For projection the process is the same with the 20 substitution of processed films and a projection lens, and the lamp housings.

Having described the construction of my invention I will now describe its operation. This invention operates substantially the same whether 25 used as a camera or a projector. When operated as a camera front wall 32a, carrying camera lens 28 is inserted in vertical grooves 31—31. Fig. 5. The lens 28 may have as an integral part of same an automatic shutter 35 provided with a trigger 30 36 to actuate same. Fig. 6. Or a separate shutter with a trigger may be independently attached to wall 32a. Or other means of timing light exposure than that described and illustrated may be employed. The front wall 32a has also disposed thereon a reciprocating rod 37 adapted to depress trigger 36.

Duplicate sensitised films 14 and 15 are threaded in the devise in the manner already described. The lamp housings A and B, Fig. 13, are removed. Figs. 5 and 14. The outside shutters 19 and 20, respectively, are detached from their respective links 77 and 78 and the shutters disposed to act as closures for the projection orifices 4 and 5 located in the respective parallel walls 2 and 3. In Fig. 5 shutters 19 and 20 are shown with their link attachments removed, as they are in this instance adapted to act as closures to prevent light from entering the dark chamber 27 except through the camera lens 28. In Fig. 15 projection shutter 19, disposed on the outside of parallel wall 2, is shown in more detail as being adapted to act as a closure for the projection opening 4. The shutter is shown as being detached from arm 74, and projection opening 4 is shown as hidden behind the opaque portion of the shutter. Shutter 20, disposed on the outside of parallel wall 3, not illustrated, is adapted in the same manner to act as a closure for projection opening 5.

Assuming parallel drive shafts 45—46 to be revolving continuously and film 14 about to move into exposure position. As frame 1 on film 14 enters exposure position at exposure opening 17 of covered film guide 9 (Fig. 16) the impact point of cam 67 on shaft 45 impinges on shoulder 65 on hub 63 of shutter arm 59 and swings arm 59 forward, holding it positively in this position. Link 76 connects shutter arm 59 with upward extending arm 75 on alined shaft 68 in dark chamber 27. Figs. 1 and 5. Upward extending arms 73—74 on alined shaft 68 connect by links 79—80, respectively, with shutters 19a—20a on inside of parallel walls 2—3. Figs. 5 and 9. In Fig. 9 the illustration shows shutter 20a disposed on the in-

side of parallel wall 3. Shutter 19a, not illustrated, occupies a similar position on the inside of parallel wall 2. When shutter 20a is in exposure position shutter 19a is in interposing position, and vice versa. When impact of cam 67 on hub shoulder 65 brings shutter arm 59 into forward position, link 76 and upward extending arm 75 act to swing alined shaft 68 forward and upward extending arm 73 swings shutter 19a to its forward position, and opening 25a in shutter 19a is brought into registering position with exposure opening 17 of covered film guide 9 on parallel wall 2. Fig. 16. At the same time shutter 20a is also brought forward by arm 74 and into interposing position at exposure opening 18 on parallel wall 3. When shutter arm 59 is impelled to its forward position link 82, in connection with pivot pin 81 fixed on the periphery of oscillating disk 141, swings the said disk and also post 142 and prism 143 around a prearranged distance, so that side 143a of prism faces exposure positioned film 14 at exposure opening 17 of channel guide 9, on vertical parallel wall 2, and side 143b of prism faces camera lens 28. By forward movement of shutter arm 59 opening 25a of shutter 19a is also brought into registering position with exposure positioned film 14.

Meanwhile countershaft 83 on removable cover 44 is driven intermittently by the mutilated pinion 87 engaging the cooperating drive gear 89 fixed on parallel drive shaft 45. Countershaft 83 has also fixed thereon pinion 91 which engages and drives gear 99 fixed on shaft 93 positioned on underside of removable cover 44. Shaft 93 has also fixed thereon sprocket barrel 97. Figs. 1 and 3. See also Figs. 11 and 12.

Pinion 87 on countershaft 83 is supplied with the concave lug 87a. Frame No. 1 on film 14 reaches exposure position at the moment drive gear 89 completes a half-turn, and lug 87a is then brought to bear against the periphery 89a of mutilated drive gear 89, which holds the countershaft 83 stationary during the half-revolution of drive gear 89 on shaft 45. Fig. 3.

The sprocket teeth on barrel 97 engage with perforations in film 14 (Fig. 4) and when drive shaft 45 makes the first half of a complete revolution film 14 is moved upward for the distance of one frame. This action brings frame 1 on film 14 into registering position with exposure opening 17 of covered film guide 9, and also into registering position with opening 25a of shutter 19a. Figs. 5 and 16. At the end of the half revolution of shafts 45 and 46 concave lug 87a releases contact with the periphery 89a of mutilated drive gear 89, and the respective gears 87 and 89 engage to revolve countershaft 83 during the next half turn of the drive shafts. Fig. 3. While film 14 is held in exposure position the duplicate mechanism driven by parallel drive shaft 46 is bringing frame No. 2 on companion film 15 into its exposure position, the film movement shielded by the opaque portion of shutter 20a. Figs. 3 and 5. At the same time cam 67 releases contact with shoulder 65, and impact point of cam 66 immediately impinges on shoulder 64, and shutter arm 59 and shutters 19a and 20a are moved to their rear position. Figs. 1, 2 and 5. This action brings shutter 19a into interposing position and shutter 20a into registering position. See Figs. 5 and 9.

When shutter arm 59 moves to its rear position links 76 and 82 cause oscillating disk 141 to swing around so that face 143a of prism 143 faces

camera lens 28, and face 143b of the prism faces exposure positioned film 15. As frame 2 on companion film 15 moves into exposure position frame 1 on film 14 moves upward to make place for frame 3, the movements of both frame 1 and frame 3 shielded by the opaque portion of shutter 19a, which has moved to its rear position. At the same time shutter 20a has also moved to its rear position, which brings opening 26a of shutter 20a into registering position with frame 2 on film 15 and also with exposure opening 18 of covered film guide 10 on parallel wall 3. See Figs. 5 and 9. The respective films 14 and 15 are alternately exposed to light from objects to be photographed in front of camera lens 28. The rays of light are transversely deflected to the respective films by the oscillating prism 143, through the respective exposure openings 17 and 18. Fig. 5. Reciprocating rod 37, in operative relation to trigger 36 on lens shutter 35 and cam 101 on cross shaft 54, regulates the time exposure of light to the respective films when the cam 101 depresses rod 37, which in turn depresses trigger 36 thereby operating lens shutter 35. Rod 37 is held in contact with cam 101 by coiled spring 38. Fig. 6. When film 14, shutter 19a and oscillating disk 141 have been brought to complete rest within dark chamber 27, during the first half of a full revolution of shafts 45 and 46, cam 101 on shaft 54 is adapted to operate with a slightly delayed action in respect to the film shutter movement. This removes any danger of movement during the exposure period. Lug 101a of cam 101 depresses reciprocating rod 37 and said rod, in turn, depresses trigger 36 of lens shutter 35 and light which is released from objects in front of lens 28 is transversely deflected to exposure positioned film 14 by oscillating prism 143. When film 15 has reached exposure position lug 101b similarly releases light to said film. Figs 5 and 6. The sensitised films are threaded in the device with the emulsions facing each other, and for projection purposes care must be taken that the processed films are rethreaded in the same manner. Good practice would indicate that distinguishing marks should be punched in the films, to designate the right and left film. In the standard motion picture camera, operating at speeds from approximately sixteen frames per second to approximately twenty-four frames per second no addition to the mechanism of the conventional camera film shutter has been found necessary, to regulate the exposure of light to the sensitised films. It is obvious that with my camera, described herein, operating at a speed approximating four frames per second, a regulation of the light flashes, in addition to the film shutters with their long exposure periods, must be provided. The novel adaptation of a lens shutter, described above, meets the requirements.

When photographing of the scene has been accomplished the exposed film is taken out and developed. The films are then rethreaded through the device, care being taken that frame No. 2 on the second film follows frame No. 1 on the first film. Upward extending arms 71 and 72 are reconnected by links 77 and 78 with the respective projection shutters 19 and 20. Lamp housings A and B are attached to the respective parallel walls 2 and 3. Front wall 32a with camera lens 28 and rod 37 is removed. Front wall 32, equipped with projection lens 34 is inserted in opposed vertical grooves 30-30. Projection can then proceed by operating the device

in exactly the same manner as when being used as a camera. If the device is used only as a camera the respective openings, variously called projection openings, projection orifices and projection apertures would still be a necessary part of the apparatus; they might then be properly called focusing apertures.

The novel arrangement of the films, with the emulsions facing each other and with the oscillating reflecting device located in the focal field between the films requires a focusing procedure in variance to the conventional method. The film channel-guides being empty, strips of ground film are placed therein, positioned so their surfaces are outlined in the focusing apertures.

The object to be photographed or, preferably, a large, vividly colored picture is placed at a suitable distance from the camera and illuminated by photo-flood lights, or other illuminants.

The lens tube is directed at the picture and the picture is transversely projected by the prism to the ground film in one aperture: the picture is properly aligned, and focused until sharp and clear; preferably observed through a strong glass. A half turn of the driving rod swings the prism around and the picture is seen on the ground film in the companion aperture. Adjusting mechanism is provided which is adapted to swing the circular disk 14¹ around until the picture is aligned equally in both apertures.

The camera still has another use for the apertures, after the ground film has been removed and the sensitized film inserted.

As has been explained each film is actuated by its own independent sprocket barrel. If the frames on the respective sensitized films, after threading, do not register and align exactly with the respective apertures, when photographing, the discrepancy, when projecting, would be magnified many times, and would render the picture worthless. Any discrepancy, observed through the apertures, may be corrected by adjusting the mechanism. Closures may then be applied to the apertures and the photographing proceed.

It is obvious that one skilled in the art, having possession of an operating model of this invention, could insert a lens tube in the device adapted to be used for taking and projecting motion pictures and provided with a lens common to both operations. No change would be required in the mechanism of the invention. The lens shutter could be adapted to remain open and the reciprocating device made inoperative during projection. The lamp housings could remain in place at all times, unless it were desired to remove them to decrease bulkiness during transportation. For studio work, where the device was to remain stationary, the lamp housings could be built as an integral part of the apparatus. During use as a camera the darkened lamp housings would provide a sufficient closure for the projection apertures; additional closures could be provided, if desired. There would be no addition of parts, or elimination of parts, in transferring from camera to projector, or vice versa. The advantage of a self-contained combination, as described herein, is obvious.

I therefore claim the right to take and project motion pictures in the combination by using a lens common to both operations, in the manner as provided in the claims. The drawings and description contain all the information necessary to adapt the device to this purpose.

In the conventional method of motion picture

70
75

projection, with one film, the cut-off blade of the shutter hides the second picture which is being moved into projection position, while the chemical change (after image) of the first picture persists in the eye. The cut-off blade of the shutter also cuts off the light during this interruption period and the screen is dark, though not visibly so, during the process of substituting the second picture for the first one.

10 The problem of the overlapping chemical changes, of making a perfect fusion of the succeeding images on the screen, in spite of the dark period and the interruption during substitution, has been the problem of those skilled in the art since motion pictures were first introduced.

15 That peculiarity of the eye, persistence of vision, while it has made motion picture projection possible, did not make perfect fusion possible without the introduction of many mechanical refinements which are still in the process of being applied.

20 In the applicant's combination there is no dark period during projection. The image of the second picture is waiting on the screen, in full light, while the chemical change of the first picture is persisting in the eye.

25 When the after-image of the first picture dissolves there is such perfect fusion with the image of the second picture, waiting in full view on the screen, that it approximates the normal observation of motion.

30 There can be no overlapping chemical changes. There is no possibility of flicker, distortion or jerky movement. During projection with the combination there is an ease and comfort experienced in the eyes and senses of the observer that is never experienced in viewing the conventional method of projection.

35 40 It is obvious that with the method of projection provided in the combination the image of the second picture must remain at rest on the screen until the chemical change of the first picture has been completed, and perfect fusion with the image of the second picture accomplished.

45 The longer rest period and slower motion of films in the combination is thus permitted and required. Perfect fusion may be accomplished, in many cases, by projecting the images on the screen at a speed approximating two frames per second.

50 55 60 65 For every complete revolution of the driving shafts in the combination one film is first light and then dark, and the companion film is first dark and then light. When one film is light, that is, in projection position and at rest, the companion film is moving up, behind the opaque portion of its shutter, to its projection position. At the moment of reaching projection position the shutters instantaneously switch. The picture being projected is shut off and proceeds to move away, behind its shutter, and the new image from the companion film remains in exposure position for the period of time that the revolving drive shafts consume in making half a revolution. If the shaft revolves at the speed of one revolution per second, an image from each film is projected on the screen in that time, or two frames per second.

70 75 When the combination is used as a motion picture camera, however, there is not the limit to the speed of the films, as in later projection of the pictures taken.

The pictures should be taken with as slow a motion of the camera mechanism as will give, in

projection, a perfect illusion of motion. It is obvious that by the installation of the lens shutter in the camera and by the elimination of the period of darkness on the screen during projection, a freedom of action is accomplished in the device not known in any motion picture apparatus now in use. The camera may operate at slow or fast taking speeds without regard to the effect of the light exposure on the sensitized films. The projector may throw images of the pictures on the screen, in alternate succession, as slow as desired without regard to the conventional methods of projection, and short of complete stoppage of the driving shaft, and still present the illusion of motion.

I claim:

1. Means for photographing views on a plurality of alternately and intermittently moving films and means for actuating said films, the combination comprising a bed, a casing with a front orifice adapted to contain a lens tube with lens and shutter inserted therein, said shutter adapted to have a trigger attached thereto and releasing and interposing means adapted to admit and exclude light to said films, respectively; a reciprocating rod movably disposed on said front wall in operative contact with said trigger and extending to the top of said wall, a cam, with opposed lugs thereon fixed on a cross shaft located in bearings on top of said casing, the respective lugs on said cam caused to be in operative contact, alternately, with the said rod, the contact of the said rod with the said shutter trigger causing the said lens shutter to open for a predetermined exposure period for regulating the admission of light from objects in front of said lens tube to said casing; means, including actuating means for transversely deflecting light, alternately, to said respective films, said deflecting means adapted to be in axial alinement with said lens tube and said exposure-positioned films, and adapted to operate in synchronous accord with said films, respectively, and said respective releasing and interposing means and said reciprocating member comprising a prism or reflector mounted on a circular surface so as to be capable of oscillating about an axis; vertical channel guides on said respective side walls of said casing adapted for the threading of films through said device and adapted to exclude light from said films except at exposure openings respectively provided therein; focusing apertures in axial alinement with said exposure openings and adapted to be fitted with closures when not in use; whereby objects in front of said lens tube by cooperative agreement between the said films and the said film shutters and the said lens shutter and the said oscillating reflecting device are photographed on said films in alternate sequence, thereby adapting the images of the pictures on said films, after processing, to be alternately projected on a screen and the said films to be threaded in a suitable projection device.

2. Means for projecting the images of pictures on a plurality of alternately and intermittently moving films, means for actuating said films, means for alternately projecting the images from said films through the said device to a projection surface thereby producing the illusion of motion comprising a moving picture combination having a bed, a casing with parallel side walls and with front wall and cover removably attached thereto, an orifice in said front wall adapted to have a lens tube inserted therein; projection apertures in said casing in axial alinement with each other

and with the said lens; releasing and interposing means on said respective side walls adapted to admit and exclude light to said films, respectively, comprising shutters with openings adapted to register with the said respective projection apertures, only one opening at a time adapted to be in a registering position and means for actuating said shutters; means, including actuating means for transversely reflecting light, within said casing, from said respective films to said lens, and to a screen, said reflecting means consisting of a prism or reflector mounted on a circular surface in axial alinement with said lens tube and said respective projection apertures so as to be capable of oscillating about an axis; means for transversely projecting light through the said respective projection apertures and said lens tube comprising lamp housings adapted to be disposed on said respective side walls of said casing, with light means therein, the rays from said respective light means adapted to be coaxial and adapted to be transversely deflected, alternately, by said oscillating reflecting device, through said lens tube to a screen.

3. Means for photographing scenes on a plurality of alternately and intermittently moving films, means for actuating said films comprising a moving picture combination having a bed, a casing, an orifice in the front wall of said casing adapted to have a lens tube inserted therein; releasing and interposing means in said casing adapted to admit and exclude light to said films, respectively, comprising film shutters with openings adapted to register with the said respective exposure orifices, only one opening at a time adapted to be in a registering position, and means for actuating said shutters; means for regulating the admission of light from objects in front of said lens tube to said respective films independent of said releasing and interposing means comprising a lens shutter attached to said lens tube, a trigger thereon, a reciprocating rod movably disposed on said front wall in operative relation to said trigger and extending to the top of said wall, a cam, with opposed lugs thereon fixed on a cross shaft located in bearings on top of the said casing, the respective lugs on said cam caused to be in operative contact, alternately, with the said rod, the said rod adapted to be reciprocated twice by the said cam for every complete revolution of the driving shaft of the apparatus, the contact of said rod with the said shutter trigger causing the said lens shutter to open and admit light for a predetermined exposure period to a sensitized film, by transverse reflection, and the second reciprocation of said rod causes the light to be exposed, in a manner similar to the first reciprocation, to the said exposure-positioned companion film and means for actuating said cross shaft; means for transversely deflecting light, alternately, from objects in front of said lens tube to said respective films comprising a prism or reflector mounted on a circular surface, or disc, in axial alinement with said lens tube and said respective exposure openings so as to be capable of oscillating about an axis and means for oscillating the prism or reflector in synchronism with the alternate and intermittent motion of the respective films, together with the cooperative action of the respective film shutters and the said lens shutter; and means for guiding said films through said casing without exposure to light except at coaxial exposure openings respectively provided therein, whereby objects in front of said lens, by cooperative agreement between the said films and the said film shutters

and the said lens shutter and the said oscillating reflecting device are photographed on said films in alternate sequence.

4. Means for photographing objects on a plurality of alternately and intermittently moving films, means for actuating said films comprising a moving picture combination having a bed, a casing with parallel side walls and with front wall and cover removably attached thereto, said casing, when closed, adapted to provide a dark chamber for the device; an orifice in said front wall adapted to have a lens tube inserted therein; coaxial focusing apertures in said respective side walls, with closure means when not in use; covered channel guides on said respective side walls having opposed internal grooves therein adapted to guide said films, respectively, through the focal plane and adapted to exclude light from said films except at coaxial exposure openings respectively provided therein; releasing and interposing means on said respective side walls adapted to admit and exclude light to said films, respectively, comprising film shutters with openings adapted to register with the said respective exposure orifices, only one opening at a time adapted to be in a registering position and means for actuating said shutters; means for regulating the admission of light through said lens tube to said respective films independent of said releasing and interposing means comprising a lens shutter, a trigger attached thereto, a reciprocating rod adapted to be in operative contact with said trigger, a cross shaft on top of said casing, and at the front thereof, a cam thereon with opposed lugs, said lugs adapted to be in actuating contact, alternately, with said rod, and means for actuating said cross shaft; means, including actuating means for transversely deflecting light, alternately, in a predetermined direction within said casing comprising a prism or reflector mounted so as to be capable of oscillating about an axis and means for oscillating the prism or reflector in suitable synchronism with the alternate and intermittent motion of the respective films together with the cooperative action of the respective film shutters and the said lens shutter whereby objects in front of said lens tube, by cooperative agreement between the said films and the said film shutters and the said lens shutter and the said reciprocating member and the said oscillating reflecting device are photographed on said films in alternate sequence, thereby adapting the said films, after processing, to be reread through a suitable projection device, so that the images of the pictures on said films may be alternately projected on a screen to produce the illusion of motion.

5. Means for photographing views on a plurality of alternately and intermittently moving films, means for actuating said films comprising a moving picture combination having a bed, a casing with parallel side walls and with front wall and cover removably attached thereto, an orifice in said front wall adapted to have a lens tube inserted therein; means, including actuating means for transversely deflecting light, alternately, in a predetermined direction within said casing comprising a prism or reflector mounted so as to be capable of oscillating about an axis and means for oscillating the prism or reflector in synchronism with the alternate and intermittent motion of the respective films and with the cooperative action of the respective film shutters and the said lens shutter means for blocking and admitting rays of light to said respective films said means consisting of independent film shut-

ters disposed, respectively, on said respective parallel walls, said shutters being provided with openings adapted to register with the respective films when in exposure position, only one opening at a time adapted to be in a registering position; means for regulating and timing the admission of light through said lens tube to said respective films independent of the said respective film shutter movements comprising a lens shutter and trigger, a reciprocating rod adapted to be in operative contact with said trigger, a cross shaft, a cam with opposed lugs thereon disposed on said cross shaft, said lugs adapted to be in operative contact, alternately, with said rod, and means for actuating said cross shaft, the action of the said cam so adjusted that the dwell of the respective films, the respective shutters and the said oscillating reflecting surface is partly completed in each instance, before the said cam is adapted to depress the said reciprocating rod; covered channel guides, respectively, on said parallel walls having opposed internal grooves therein adapted to guide said films, respectively, through the focal plane and adapted to exclude light from said films except at coaxial exposure openings provided therein whereby objects in front of said lens, by cooperative agreement between the films and film shutters and the said lens shutter and the said reciprocating member and the said oscillating reflecting device are photographed on said films in alternate sequence, thereby adapting the said device to accomplish photographing at a plurality of predetermined speeds and also with a plurality of selectively reduced speeds, thereby adapting the images of the pictures on the said respective films to be projected through a suitable projection device with the illusion of motion at selectively reduced speeds and thereby films produced by the said camera are adapted to be projected through the said projection device at a reduced consumption in film footage to coordinate with the said reduction in speed.

6. Means for photographing views on a plurality of films adapted to move alternately and intermittently through the focal plane of the apparatus, means for actuating said films comprising a moving picture combination having a bed, a casing with parallel side walls and with front wall and cover removably attached thereto, an orifice in said front wall adapted to have a lens tube inserted therein, a lens shutter adapted to be attached thereto with a trigger thereon; means for blocking and admitting rays of light to said respective films consisting of independent film shutters disposed, respectively, on said respective parallel walls, means for operating the respective film shutters in combination and in cooperative movement with the respective films, the oscillating reflecting device and the said lens shutter comprising a driving shaft on said removable cover adapted to have fixed thereon, at the rear thereof, a manually operated crank, a companion shaft, adapted to be parallel to said crank operated shaft and to the right thereof, said parallel shafts extending lengthwise of and rotatably mounted, respectively, in bearings on said removable cover and having secured thereon intermittent gears which are adapted to engage other gears respectively fixed on countershafts, said countershafts adapted to be rotatably mounted in bearings on the said removable cover so that intermittent motion is adapted to be imparted to the said countershafts when the respective parallel drive shafts are rotated; miter gears of identical ratio fixed, respectively, to the

contiguous front ends of said parallel drive shafts, said gear, respectively, adapted to engage similar gear, of like ratio, disposed on the respective ends of a cross shaft similarly resting in bearings on said removable cover, and means for actuating said driving shafts; means adapted to regulate and time the admission of light through said lens tube to said respective exposure openings comprising a lens shutter and trigger, a reciprocating rod in actuating contact with said trigger, a cross shaft, a cam with opposed lugs thereon disposed on said cross shaft and adapted to be in operative contact with said rod, the action of said cam so adjusted that the dwell of the respective films, the respective shutters and the said oscillating reflecting surface is adapted to be partly completed in each instance before the said cam is caused to depress the said reciprocating rod, and means for actuating said cross shaft; means, including actuating means for transversely deflecting light, alternately, from objects in front of said lens tube to said respective films comprising a prism or reflector mounted on a circular surface or disk, in axial alinement with said lens tube and said respective exposure openings, so as to be capable of oscillating about an axis and means for oscillating the prism or reflector in suitable synchronism with the alternate and intermittent motion of the respective films together with the cooperative action of the respective film shutters and the said lens shutter; covered channel guides, respectively, on said parallel walls adapted to guide said films, respectively, through the focal plane and adapted to exclude light from said films except at coaxial exposure openings provided therein; and means for actuating the said respective shutters, the respective films, the reciprocating member and the oscillating reflecting means in synchronous accord whereby objects in front of said lens, by cooperative agreement between the said films and film shutters, the said reciprocating member and the said oscillating reflecting means are photographed on said films in alternating sequence, thereby producing films which are adapted to be threaded through a suitable projection device and projected to give the illusion of motion.

7. A combined camera and projector for taking moving pictures on and projecting them from a plurality of alternately and intermittently moving films whereby the device is adapted to accomplish photographing and projecting of motion pictures at a plurality of predetermined speeds and a plurality of selectively reduced speeds, in a manner not known and in a manner not used or known in any known combination of moving picture camera and projector and at slower speeds than now accomplished or known in any conventional or known type of moving picture camera and projector comprising a casing, a lens system at the front thereof adapted for both taking and projecting the pictures with a lens common to both operations, a shutter and trigger on said lens system adapted to be rendered inactive when not in use; means for adapting said lens shutter to open and admit light, for a predetermined exposure period, to said films independent of said blocking and releasing means consisting of a reciprocating member positioned on the front wall of said casing whose lower end is adapted to be in operative contact with said trigger and whose upper end is in actuating contact with a cam having opposed lugs thereon, said cam being disposed on a cross shaft located in bearings on the top of said casing, the respec-

tive lugs on said cam caused to be in operative contact, alternately, with the said rod, the said rod adapted to be reciprocated twice by the said cam for every complete revolution of the driving shaft of the apparatus, the contact of the said rod with the said shutter trigger causing the said lens shutter to open and admit light, for a predetermined exposure period, to a sensitized film by transverse reflection, and the second reciprocation of the said rod causes the said light to be exposed, in a manner similar to the first reciprocation, to the said exposure-positioned companion film and means for actuating the said cross shaft; an oscillating reflecting means within said casing adapted to receive light from objects in front of said lens and transversely project said light, in alternate sequence, to said respective films or alternately receive light from said respective films and transversely project said light through said lens to a projection surface comprising a prism or reflector mounted on a circular surface in axial alinement with said lens tube and said respective exposure openings so as to be capable of oscillating about an axis and means for oscillating the prism or reflector in synchronism with the alternate and intermittent motion of the respective films together with the cooperative action of the respective film shutters and the said lens shutter; projection apertures in the walls of said casing adapted to be coaxial with each other and with the said oscillating reflecting means and provided with closures when not in use; means for intermittently moving the respective films through the focal plane within said casing without exposure to light except at coaxial exposure openings, said exposure openings adapted to be in axial alinement with the said projection apertures so that the said films can alternately receive rays of light from objects in front of the said lens system or project light through the lens system; means for transversely projecting light through said respective projection apertures and said lens system comprising lamp housings adapted to be disposed, respectively, on the outside of said casing with light means therein, the rays from said respective light means adapted to be coaxial with each other and with said projection apertures and adapted to be transversely deflected, alternately, by said oscillating reflecting means through said lens system to a screen or projection surface; means for blocking and releasing rays of light to said respective films comprising film shutters with openings adapted to register with the said exposure-positioned films, only one opening at a time adapted to be in a registering position and means for actuating the respective films and the oscillating reflecting means and the said blocking and releasing means and the said lens shutter in synchronous accord whereby objects in front of said lens, by cooperative agreement between the said films and film shutters and the said reciprocating member and the said oscillating reflecting device are photographed on said films in alternating sequence and whereby the images of the pictures on said films, after processing and rethreading of said films, are adapted to be projected, in alternating sequence on a screen, thereby producing the illusion of motion.

8. A combined camera and projector for taking moving pictures on and projecting them from a plurality of alternately and intermittently moving films comprising a casing, a lens system at the front thereof for taking or projecting the

pictures, a shutter and trigger attached to said lens system and adapted to be rendered inoperative when not in use, a reciprocating member in operative contact with said trigger, a cam with opposed lugs thereon disposed on a cross shaft, said lugs adapted to be in operative contact, alternately, with said reciprocating member and said cam adapted to be rendered inoperative when not in use and means for actuating said cross shaft; an oscillating reflecting means within said casing adapted to receive light from objects in front of said lens and transversely project said light, alternately, to said respective films or alternately receive light from said respective films and project said light through said lens to a projection surface; projection apertures in the walls of said casing adapted to be coaxial with each other and with the said oscillating reflecting means and the said lens system and provided with closures when not in use; means for moving the respective films, alternately, through the focal plane in said casing so that the said films can receive rays of light from objects in front of the said lens or be adapted to project light through the said lens; means for transversely projecting light through said respective projection apertures and said lens system comprising lamp housings adapted to be disposed on the outside of said casing with light means therein, the rays from said respective light means adapted to be coaxial and adapted to be transversely deflected, alternately, by said oscillating reflecting means through said lens system to a screen or projection surface; means for blocking and releasing rays of light to said respective films, means for regulating the admission of light through said lens system independent of said blocking and releasing means and means for actuating the said reciprocating member, the blocking and releasing means, the respective films and the oscillating reflecting means in synchronous accord whereby the combination is adapted to accomplish the photographing and projecting of motion pictures at a plurality of predetermined speeds and a plurality of selectively reduced speeds, in a manner not known and in a manner not used or known in any known combination of moving picture camera and projector, and at slower speeds than now accomplished or known in any conventional or known type of combined motion picture camera and projector, whereby the projector, in cooperative coordination with the camera action, projects the films produced by that portion of the device devoted to camera action at a reduction in speed and thereby is adapted to project motion pictures at a reduction in film footage in comparison with the known or conventional type of combined camera and projector.

9. In a motion picture camera the combination with a case containing mechanism to actuate a plurality of alternately and intermittently moving films, a front lens system supplied with shutter and trigger, a reciprocating rod movably disposed on said front wall in operative relation to said trigger and extending to the top of said wall, a cam with opposed lugs thereon fixed on a cross shaft located in bearings on top of said casing, the respective lugs on said cam caused to be in actuating contact, alternately, with the said rod, the said rod adapted to be reciprocated twice by the said cam for every complete revolution of the driving shaft of the apparatus, the contact of the said rod with the said shutter trigger causing the said lens shutter to open and admit light for a predetermined exposure period,

independent of said releasing and interposing means, to a sensitised film by transverse reflection and the second reciprocation of the said rod causes the light to be exposed, in a manner similar to the first reciprocation to the said exposure-positioned companion film and means for actuating the said cross shaft; means for transversely deflecting light, alternately, from objects in front of the said lens tube to said respective films comprising a prism or reflector mounted on a circular surface in axial alinement with the said lens tube and said respective exposure openings so as to be capable of oscillating about an axis and means for oscillating the prism or reflector in synchronism with the alternate and intermittent motion of the respective films, together with the cooperative action of the respective film shutters and the said lens shutter; releasing and interposing means within said casing adapted to admit and exclude light to said films, respectively, comprising film shutters with openings adapted to register with the said respective films, only one opening at a time adapted to be in a registering position; channel guides within said case adapted to direct the respective films through the focal plane and means for actuating the said reciprocating member the respective films and the oscillating reflecting means in synchronous accord whereby objects in front of said lens, by cooperative agreement between the said films and film shutters and the said reciprocating member and the said oscillating reflecting device are photographed on said films in alternate sequence thereby adapting the said device to accomplish photographing at a plurality of predetermined speeds and also with a plurality of selectively reduced speeds and at slower speeds than now accomplished, or known, in the conventional or known type of motion picture camera, thereby adapting the images of the pictures on the said films to be projected, with the illusion of motion, in a suitable projection apparatus at selectively reduced speeds, to coordinate with the speeds at which the said films were produced by the said camera action, and at slower speeds than now accomplished, or known, in the conventional or known type of motion picture projection device, whereby the said films are adapted to be projected at a reduced consumption in film footage to coordinate with the said reduction in speed.

10. In a motion picture device the combination with mechanism adapted to actuate a plurality of alternately and intermittently moving films, and means for actuating said mechanism, a system of shutters adapted to block and release light to said respective films, and means for actuating said shutters, a closed casing with a front lens system therein supplied with shutter and trigger, a reciprocating member whose lower end is adapted to be in operative contact with said trigger and whose upper end is in actuating contact with a cam, said cam being disposed on a cross shaft, and means for actuating said cross shaft; an oscillating reflecting means within said casing adapted to transversely deflect light, in alternate sequence, from objects in front of said lens to the said respective films, and means for actuating the said respective shutters, the reciprocating member, the respective films and the oscillating reflecting means in synchronous accord, whereby objects in front of said lens, by cooperative agreement between the said films and film shutters and the said reciprocating member and the said oscillating reflecting de-

vice are photographed on said films in alternate sequence.

11. In a motion picture device the combination with a plurality of alternately and intermittently moving films, mechanism to actuate said films and means to actuate said mechanism, a system of shutters adapted to block and release light to said films, and means for actuating said shutters, a casing with a front lens system therein, an oscillating reflecting means within said casing adapted to transversely deflect light, in alternate sequence, from said respective films through said lens system to a projection surface, and means for actuating said reflecting means, projection apertures in the respective side walls of said casing adapted to be in axial alinement with each other and with the said oscillating reflecting means; lamp housings disposed, respectively, on the side walls of said casing with light means therein, rays from said light means adapted to be coaxial and adapted to be in alinement with said respective projection apertures and said oscillating reflecting means, and means for actuating the said respective shutters, the respective films and the oscillating reflecting means in synchronous accord, whereby light rays from said respective lamp housings are adapted to be transversely deflected, alternately, through said films and said lens system to a projection surface whereby images of the pictures on the said films are adapted to be alternately projected to a screen thereby producing the illusion of motion.

12. In a combined motion picture camera and projector the combination with a plurality of alternately and intermittently moving films and a film actuating mechanism, a casing containing a front lens organization mounted therein with lens shutter and trigger attached thereto, means for adapting said lens shutter to open and admit light, for a predetermined exposure period, to said films independent of said respective film shutters and said shutter adapted to be rendered inoperative when not in use; a reciprocating member adapted to be in operative contact with said trigger and adapted to be actuated by a cam with opposed lugs thereon, disposed on a cross shaft and means for actuating said cross shaft; projection apertures in the respective side walls of said casing adapted to be in axial alinement with each other and with said lens and provided with closures when not in use; an oscillating reflecting means within said casing in axial alinement with said respective projection apertures and said lens adapted to receive light from objects in front of said lens and transversely project said light, alternately, to said respective films, or alternately receive light from said respective films and project said light through said lens to a screen and means to actuate said reflecting means; channel guides adapted to exclude light from said films except at exposure openings respectively provided therein, said exposure openings adapted to be in axial alinement with said projection apertures and said lens; film shutters adapted to block and release light to said respective films and means to actuate said shutters and means to admit light to said respective films for a predetermined exposure period independent of said blocking and releasing means; lamp housings disposed, respectively, on the side walls of said casing with light means therein, rays from said light means adapted to be coaxial and adapted to be in alinement with said respective projection apertures and said oscillating reflecting means and means for actuating the said respective shutters, the re-

spective films, the reciprocating member and the oscillating reflecting means in synchronous accord, whereby objects in front of said lens, by cooperative agreement with the said films and film shutters and the said reciprocating member and the said oscillating reflecting means are photographed on said films in alternate sequence, or whereby the light rays from said respective lamp housings are adapted to be transversely deflected, in alternate sequence, through said lens system to a projection surface whereby the combination is adapted to accomplish photographing and projecting of motion pictures at a plurality of predetermined speeds and a plurality of selectively reduced speeds in a manner not known and in a manner not used or known in any known combination of moving picture camera and projector, and at slower speeds than now accomplished, or known, in any conventional or known type of combined motion picture camera and projector, whereby the projector of the application, in cooperative coordination with the camera action, projects the films produced by that portion of the device devoted to camera action at a reduction in speed and thereby is adapted to project motion pictures at a reduction in film footage in comparison to the results produced by the known or conventional type of combined motion picture camera and projector.

13. A camera for taking motion pictures on a plurality of alternately and intermittently moving films the combination adapted to accomplish photographing at a plurality of predetermined speeds and also with a plurality of selectively reduced speeds comprising a film actuating mechanism, a closed casing, a system of lenses at the front thereof for taking the pictures said lens system having a lens shutter and trigger disposed thereon; releasing and interposing means in said casing comprising film shutters with openings to admit and exclude light to said respective films, only one opening at a time adapted to be in a registering position, and means for actuating said shutters; the said films adapted to receive rays of light, alternately, from objects in front of the lens system; a reciprocating member adapted to be in operative contact with the trigger of said lens shutter for regulating the admission of light, for a predetermined exposure period, from objects in front of the said lens system to the said films, independent of said film shutters; a cam with opposed lugs thereon, disposed on a cross shaft, said lugs adapted to be in actuating contact, alternately, with said reciprocating member and means for actuating said cross shaft; means, including actuating means, for transversely deflecting light, alternately, to said respective films, consisting of an oscillating reflecting surface, or mirror, said mirror adapted to be in the focal plane of the said lens system and disposed so as to be capable of oscillating about an axis, and means for actuating the said respective shutters, the respective films, the reciprocating member and the oscillating reflecting means in synchronous accord, whereby objects in front of said lens, by cooperative agreement between the said films and film shutters the said reciprocating member and the said oscillating reflecting means are photographed on said films in alternate sequence whereby the images of the pictures on the said respective films are adapted to be projected in a suitable projection device with the illusion of motion and at slower speeds than now known or used 75 in any known or conventional type of projection

device, to accord with the said slower speeds of the film produced by the said camera device.

14. In a motion picture device the combination with mechanism adapted to actuate a plurality of alternately and intermittently moving films, and means for actuating said mechanism, a system of shutters adapted to block and release light to said respective films, said shutters, respectively, provided with openings adapted to register with the respective exposure-positioned films, only one opening at a time adapted to be in a registering position, and said respective shutters adapted to remain continuously at rest, except for instantaneous movements from exposure position to interposing position, and vice versa; and means for actuating said shutters; a closed casing with a front lens system therein supplied with shutter and trigger, means for adapting said lens shutter to open and admit light, for a predetermined exposure period, to said films independent of said respective film shutters consisting of a reciprocating member positioned on front wall of said casing whose lower end is adapted to be in operative contact with said trigger and whose upper end is in actuating contact with a cam having opposed lugs thereon, said cam being disposed on a cross shaft, and means for actuating said cross shaft; an oscillating reflecting means within said casing adapted to transversely deflect light, in alternate sequence, from objects in front of said lens to the said respective films comprising a prism or reflector mounted on a circular surface, or disk, in axial alinement with said lens tube and said respective exposure openings so as to be capable of oscillating about an axis, and adapted to remain continually at rest, except for instantaneous movements so as to be caused to register, successively, with the said alternately exposed films, and means for oscillating the prism, or reflector, in synchronism with the alternate and intermittent motion of the respective films, together with the cooperative action of the respective film shutters and the said lens shutter; and means for guiding the said respective films through the focal field within said casing without exposure to light except at coaxial exposure openings respectively provided therein, whereby objects in front of said lens, by cooperative agreement between the said films and the said film shutters and the said lens shutter and the said oscillating reflecting device are photographed on said films in alternate sequence, thereby adapting the said device to produce films which, after processing, may be threaded through a suitable projection device for the purpose of producing the illusion of motion.

15. A motion picture combination adapted to have a plurality of alternately and intermittently moving processed films threaded through the device and means for actuating said films comprising a bed, a casing with an orifice in the front wall adapted to have a lens tube inserted therein; releasing and interposing means in said casing adapted to admit and exclude light from said respective films to said lens system comprising film shutters with openings adapted to register with the said exposure-positioned films, only one opening at a time adapted to be in a registering position and means for actuating said shutters; projection apertures in the respective side walls of said casing, adapted to be coaxial with each other and with said lens tube; lamp housings removably attached to the respective side walls of said casing, with light means therein, rays from said light means adapted to be coaxial with each

other and with the said respective projection apertures and adapted to project the images of the pictures on said films, alternately, to the said oscillating reflecting device; means for transversely projecting light, alternately, from the respective films through the said lens tube to a screen comprising a prism or reflector mounted on a circular surface, or disk, so as to be capable of oscillating about an axis, and in axial alinement with said lens tube and the light rays from said respective lamp housings and means for oscillating the prism or reflector in synchronism with the alternate and intermittent motion of the respective films, together with the cooperative action of the respective film shutters whereby images of the pictures on the respective films, by cooperative agreement between the said films and the said film shutters and the said oscillating reflecting device are adapted to be alternately projected on a screen, thereby producing the illusion of motion.

16. A motion picture combination adapted to have a plurality of alternately and intermittently moving processed films threaded through the device and means for actuating said films comprising a bed, a casing with an orifice in the front wall adapted to have a lens tube inserted therein; releasing and interposing means in said casing adapted to admit and exclude light from said respective films to said lens system, and to a screen comprising film shutters with openings adapted to register with the said exposure-positioned films, only one opening at a time adapted to be in a registering position and means for actuating said shutters; projection apertures in the respective side walls of said casing, adapted to be coaxial with each other and with said lens tube; lamp housings removably attached to the respective side walls of said casing, with light means therein, rays from said light means adapted to be coaxial with each other and with the said respective projection apertures and adapted to project the images of the pictures on said films, alternately, to the said oscillating reflecting device, and to a screen; means for transversely projecting light, alternately, from said respective films through said lens tube to a screen comprising a prism or reflector mounted on a circular surface, or disk, so as to be capable of oscillating about an axis, and in axial alinement with said lens tube and the light rays from said respective lamp housings and means for oscillating the prism or reflector in synchronism with the alternate and intermittent motion of the respective films, together with the cooperative action of the respective film shutters whereby images of the pictures on the respective films, by cooperative action between the said films and the said film shutters and the said oscillating reflecting device are adapted to be alternately projected on a screen, the said shutters being adapted to release one ray of light to the screen the moment the companion ray of light is obscured, thereby eliminating any period of darkness between projection periods, whereby the said images are adapted to present the illusion of motion by being projected at reduced speed, in comparison to the conventional or known method of projection, thereby adapting projection to proceed at an obviously reduced consumption of film footage per second.

17. Means for photographing scenes on a plurality of alternately and intermittently moving films, means for actuating said films comprising a moving picture combination having a bed, a casing, an orifice in the front wall of said casing

adapted to have a lens tube inserted therein; releasing and interposing means in said casing adapted to admit and exclude light to said films, respectively, comprising film shutters with openings adapted to register with the said respective exposure orifices, only one opening at a time adapted to be in registering position and means for actuating said shutters; means for regulating the admission of light from objects in front of said lens tube to said respective films independent of said releasing and interposing means comprising a lens shutter attached to said lens tube, a trigger thereon, a reciprocating rod movably disposed on said front wall in operative relation to said trigger and extending to the top of said wall, a cam, with opposed lugs thereon fixed on a cross shaft located in bearings on top of said casing, the respective lugs on said cam caused to be in operative contact, alternately, with the said rod, the said rod adapted to be reciprocated twice by the said cam for every complete revolution of the driving shaft of the apparatus, the contact of the said rod with the said shutter trigger causing the said lens shutter to open and admit light for a predetermined exposure period to a sensitized film by transverse reflection, and the second reciprocation of said rod causes the said light to be exposed, in a manner similar to the first reciprocation, to the said exposure-positioned companion film and means for actuating the said cross shaft; means for transversely deflecting light, alternately, from objects in front of said lens tube to said respective films comprising a prism or reflector mounted on a circular surface, or disk, in axial alinement with said lens tube and said respective exposure openings so as to be capable of oscillating about an axis and means for oscillating the prism or reflector in synchronism with the alternate and intermittent motion of the respective films, together with the cooperative action of the respective film shutters and the said lens shutter; and means for guiding the said films through the said casing without exposure to light except at coaxial exposure openings respectively provided therein; whereby objects in front of said lens, by cooperative agreement between the said films and the said film shutters and the said lens shutter and the said reciprocating member and the said oscillating reflecting device are photographed on said films in alternative sequence thereby adapting the said device to accomplish photographing at a plurality of predetermined speeds and also with a plurality of selectively reduced speeds thereby adapting the images of the pictures on the said films to be projected, with the illusion of motion, in a suitable projection apparatus at selectively reduced speeds and at slower speeds than now accomplished, or known, in the conventional or known type of projection devices.

18. A motion picture combination adapted to have a plurality of alternately and intermittently moving processed films threaded through the device and means for actuating the said films comprising a bed, a casing with an orifice in the front wall adapted to have a lens tube inserted therein; releasing and interposing means in said casing adapted to admit and exclude light from said re-

spective films to said lens system, and to a screen comprising film shutters with openings adapted to register with the said exposure-positioned films, only one opening at a time adapted to be in a registering position; said shutters adapted to remain continually at rest, except for instantaneous movements from registering position to interposing position, and vice versa and means for actuating said shutters; projection apertures in the respective side walls of said casing adapted to be coaxial with each other and with said lens tube; lamp housings removably attached to the respective side walls of said casing, with light means therein, rays from said light means adapted to be coaxial with each other and with the said respective projection apertures, the said shutters adapted to release one light ray to the screen the moment the companion light ray is obscured, thereby eliminating any period of darkness between projection intervals, the rays from said light means adapted to project the images of the pictures on said films, alternately, to the said oscillating reflecting device, and to a screen; means for transversely projecting light, alternately, from said respective films through said lens system to a screen comprising a prism or reflector mounted on a circular surface, or disk, so as to be capable of oscillating about an axis, and in axial alinement with said lens tube and the light rays from said respective lamp housings and means for oscillating the prism or reflector in synchronism with the alternate and intermittent motion of the respective films, together with the cooperative action of the respective film shutters whereby images of the pictures on the respective films, by cooperative action between the said films and the said film shutters and the said oscillating reflecting device are adapted to be alternately projected on a screen, whereby the said images are caused to present the illusion of motion by being projected at selectively reduced speeds, and thereby the said device is adapted to project motion pictures at a reduced consumption of film footage to coordinate with the said reduction in speed.
